UNITED STATES PATENT OFFICE.

SOLOMON HIMMEL, OF BALTIMORE, MARYLAND.

DISPLAY-RACK.

1,282,576.

Specification of Letters Patent. Patented Oct. 22, 1918.

Application filed February 17, 1915. Serial No. 8,818.

To all whom it may concern:

Be it known that I, SOLOMON HIMMEL, a citizen of the United States, residing at Baltimore, and State of Maryland, have invented new and useful Improvements in Display-Racks, of which the following is a specification.

This invention relates to improvements in display racks for garments and the like.

10 One of the objects of the invention is to provide improved means whereby garments may be conveniently and compactly stored in dust proof cases and yet be readily accessible for exhibition to a customer by a sales-
15 man. A further object is to provide an improved rack capable of being readily removed from the case, and which may be free to revolve when moved to the forward position, to display the goods supported there-
20 by. A further object is to provide means for preventing rotation of the rack while in the case. A further object is to provide means for preventing the rack from being pushed back into the case when in its for-
25 ward position, until the rack is in alinement with the rear wall of the case.

The invention will be hereinafter fully set forth and particularly pointed out in the claims.

30 In the accompanying drawings:—

Figure 1 is a plan view illustrating a case containing my improved display rack, the latter being shown in its rearmost position. Fig. 2 is a similar view with the rack in its forward position. Fig. 3 is a detail sectional view illustrating the guiding features. Fig. 4 is a plan view diagrammatically illustrating the operation. Fig. 5 is a detail view of a modification.

40 Referring to the drawing, 10 designates a case of any suitable or preferred construction, the bottom being provided with a channel 11, the upper edges of which form guides 12 between which the carriage 13 is mounted to reciprocate. Said carriage supports a rotatable shaft 14 provided with a cross-head 15, said cross-head supporting the parallel arms 16 from which the garments or the like, are to be suspended. Secured to said shaft 14 is a disk 17 provided with recesses 18 in its edge, which recesses form cam pockets for the reception of a roller 19 mounted upon a lever 20 pivoted at one end to the carriage 13, the free end of said lever being connected with a spring 21 which acts to hold the roller 19 in engagement with

the edge of the disk 17. Depending from the underside of disk 17 are two pairs of guide engaging members or rollers a a' and b b' respectively. Secured to the bottom of the case is a stationary guide member 22 the longitudinal edges of which pass between the guide-engaging members a and a' , and b and b' , so that said guide-engaging members are in engagement with the outer surfaces of said sides. It will be noted that the distance between the members a and a' and b and b' respectively is greater than the distance between the members a and b and a' and b' . In other words the pairs of 65 guide-engaging members are separated by a distance less than the width of the guide 22. Said guide 22 is of such length that the rollers b and b' will move out of engagement with the guide when the carriage is brought 70 to its outermost position, whereupon the shaft 14 and the rack supported thereby is free to rotate, subject to such restraint as may be imposed by the spring pressed lever 20. Secured to the floor of the case beyond 75 the forward end of the guide member 22 is an anchor member 23, which is preferably oblong in shape and provided with rounded ends.

In practice, when the carriage is in its 85 rearmost position within the case, the guide-engaging members, by reason of their engagement with the upstanding sides of the guide 22, prevent rotation of the shaft 14, and the parts carried thereby. This rotation is prevented until the carriage has been moved to the front of the case a sufficient distance for the members b and b' to clear the forward end of the guide. The axis of the shaft 14 is then over the center of the 90 anchor member 23, whereupon the shaft may be rotated, the guide engaging members passing between the anchor member 23 and the forward end of the guide 22. The spring pressed lever 20 acting upon the disk 17, and particularly the recesses 18 thereof, tends to arrest rotation of the shaft when the arms 16 of the rack are parallel with the back of the case. It will be observed that the guide-engaging members are so positioned that if an attempt is made to move the rack and carriage rearwardly before the rack is in alinement with the rear wall of the case, said guide-engaging members, co-operating with the anchor member 23 will 100 prevent such rearward motion. In other words the carriage cannot be moved rear- 105 110

wardly until the members *a* and *b*, and *a'* and *b'* are in a position to pass on opposite sides of the guide member.

In Fig. 5 I have illustrated a slight modification in which the anchor member 30 is rotatably mounted on the bottom of the channel 11 by means of a central pivot 31, said anchor member being normally held in alinement with the guide member 22 by a spring 32, engaging a disk 33, rigidly secured to the anchor member. The ends of the anchor member are curved on an arc struck from the pivot center and the end of the guide member is correspondingly recessed. In operation as the rack is drawn forward the guide rollers engage the sides of the anchor member 30, but it will be observed that the rack cannot be rotated until the center of shaft 14 registers with the center of pivot 31. The spring 32 will serve to retard rotation of member 30 sufficiently to bring the latter into register with the guide 22. If an attempt is made to move the rack and carriage rearwardly before the rack is in alinement with the case, the rollers *a*—*a'* and *b*—*b'* will prevent such rearward movement because of their engagement with anchor member 30 and their position with respect to the guide member 22, it being impossible to disengage the rollers from the anchor member until the latter is alined with the guide member.

Having thus explained the nature of my invention, and described an operative manner of constructing and using the same, although without attempting to set forth all of the forms in which it may be made, or all of the forms of its use, what I claim is:—

1. A display rack comprising a case, a rotatable rack member mounted to reciprocate within said case, means for normally preventing rotation of said rack member, rotatable means engaged by the rack member when in one extremity of its reciprocation, 45 to permit rotation thereof, and means for normally maintaining said rotatable means in position to be engaged by said rack during reciprocable movement of the latter.

2. A display rack comprising a case, a rotatable rack member mounted to reciprocate within said case, a guide within the case engaged by the rack member to normally prevent rotation of said rack member, and rotatable means independent of the guide and 55 engaged by the rack member when in one extremity of its reciprocation, to permit rotation thereof, and means for normally maintaining said rotatable means in position to

be engaged by said rack during reciprocable movement of the latter.

60

3. A display rack comprising a case, a rotatable rack member mounted to reciprocate in said case, a guide for said rack member provided with independent stationary and rotatable portions, and means for normally holding the rotatable portion in alinement with the stationary portion.

4. A display rack comprising a case, a rotatable rack member mounted to reciprocate in said case, a guide for said rack member provided with independent stationary and rotatable portions, and means for normally holding the rotatable portion in alinement with the stationary portion, said rotatable member being spaced from one end of the 75 stationary member.

5. The combination with a case provided with carriage guides, a carriage mounted to reciprocate in said carriage guides, a stationary guide located below said carriage, a rotatable rack member supported by said carriage, a disk attached to said rack member and rotatable therewith, depending members attached to said disk and arranged to engage the sides of said stationary guide, a 80 rotatably supported anchor member spaced from the forward extremity of said stationary guide and positioned to form a continuation thereof, and means for holding said anchor member normally in alinement with 85 the guide member.

6. The combination with a case provided with carriage guides, a carriage mounted to reciprocate in said carriage guides, a stationary guide located below said carriage, a rotatable rack member supported by said carriage, a disk attached to said rack member and rotatable therewith, two sets of depending members attached to said disk, the members of each set being normally located on 100 opposite sides of said stationary guides, the said sets being separated by distance less than the distance between the pins of each set, rollers carried by said members to engage said guide, an anchor member spaced 105 from the forward extremity of said stationary guide, and means coöperating with said disk to position said depending members with respect to said stationary guide.

In testimony whereof I have hereunto set 110 my hand in presence of two subscribing witnesses.

SOLOMON HIMMEL.
